UNITED STATES PATENT OFFICE.

ERNEST VICTOR TOMLINSON, OF BUFFALO, NEW YORK.

DESIGN FOR A CAMP-STOOL.

SPECIFICATION forming part of Design No. 34,455, dated April 30, 1901.

Application filed January 26, 1901. Serial No. 44,952. Term of patent 3½ years.

To all whom it may concern:

Be it known that I, ERNEST VICTOR TOMLINSON, a subject of His Majesty the King of Great Britain, residing at Buffalo, in the county of Erie and State of New York, have invented and produced a new and original Design for Camp-Stools, of which the following is a specification, reference being had to the accompanying drawings, forming part thereof.

10 This invention consists in the design for a camp-stool, as illustrated in the accompanying drawings, in which—

Figure 1 shows an elevation of the design, and Fig. 2 a top plan view of the same.

15 Referring to the drawings, the body 1 of the stool is of cylindrical shape, having the handle 2 at its center. Diverging from the base of this cylinder 1 is the tripod arrangement of legs 3.

20 The seat of the stool is formed by a series of curved arms diverging upwardly and outwardly from the top of the cylinder 1, forming a seat, which is semicylindrical in general outline or cup-shaped, the upper face being

unobstructed by the usual cross-webbing. 25 Each of the arms forming the cup-shaped seat are made from a double wire, each strand of wire being curved outwardly and inwardly in a lateral direction, (to and from each other,) so as to form an elongated diamond-shaped 30 figure, as shown in Fig. 2.

The leading feature of the design consists in the cup-shaped wire frame or seat.

Minor features are the diamond-shaped radiating curved arms and carrying-handle located at the center of the cylinder. 35

Having thus described my design, what I claim, and desire to secure by Letters Patent, is—

25 The design for a camp-stool substantially 40 as shown and described.

In testimony whereof I have hereunto set my hand in the presence of two subscribing witnesses.

ERNEST VICTOR TOMLINSON.
